Primary Examiner — Catherine R Oliver-Garcia(57) **CLAIM**

The ornamental design for fishing lure knocker device, as shown and described.

DESCRIPTION

FIG. 1 is a perspective view of the fishing lure knocker device of the present invention;

FIG. 2 is another perspective view thereof;

FIG. 3 is a top plan view thereof;

FIG. 4 is a bottom plan view thereof;

FIG. 5 is a side elevation view thereof;

FIG. 6 is an opposite side elevation view thereof;

FIG. 7 is a front elevation view thereof; and,

FIG. 8 is a rear elevation view thereof.

The broken lines showing portions of the fishing lure knocker device is included for the purpose of illustrating only and forms no part of the claimed design.

1 Claim, 8 Drawing Sheets(56)
